[57] CLAIM

The ornamental design for a step plate, substantially as shown and described.

DESCRIPTION

FIG. 1 is a perspective view of a step plate embodying the present design;

FIG. 2 is a top plan view of the step plate shown in FIG. 1;

FIG. 3 is an elevational view of the side shown in FIG. 1;

FIG. 4 is an elevational view of the side opposite that shown in FIGS. 1 and 3;

FIG. 5 is a bottom elevational view;

FIG. 6 is an elevational view of the end opposite that seen in FIG. 1; and

FIG. 7 is an enlarged cross sectional view taken on line 7—7 of FIG. 5.

The name "John Doe" is included only to illustrate the use of a personalized plate insert secured in a longitudinal groove on the upper surface of the step plate.
